CLAIM

The ornamental design for a specialized receptacle, as shown and described.

DESCRIPTION

FIG. 1 is a front elevational view of a specialized receptacle according to a first embodiment of my design. The rear elevational view is a mirror image of the front elevational view.

FIG. 2 is a right side elevational view thereof. The left side elevational view is a mirror image of the right side elevational view.

FIG. 3 is a top elevational view thereof.

FIG. 4 is a bottom elevational view thereof.

FIG. 5 is a front, top, right side perspective view thereof.

FIG. 6 is a front, top, right side perspective view of my design according to a second embodiment, whereby a central, length-running portion thereof is curved from the front and back toward the middle, and whereby the front, rear, left side and right side elevational views are the same as in the first embodiment; and,

FIG. 7 is a top elevational view thereof.

The broken lines in the drawings depict portions of the specialized receptacle that form no part of the claimed design.
